UNITED STATES PATENT OFFICE.

JOHN BROWN, OF PRESTON, IDAHO.

SWITCH-ACTUATING MECHANISM.

1,262,168.

Specification of Letters Patent.

Patented Apr. 9, 1918.

Application filed May 14, 1917. Serial No. 168,485.

To all whom it may concern:

Be it known that I, JOHN BROWN, a citizen of the United States, residing at Preston, in the county of Franklin and State of Idaho, have invented a new and useful Switch-Actuating Mechanism, of which the following is a specification.

The present invention relates to a mechanism for controlling and operating a pump, which can be used for automatically pumping the water out of the cellar or for otherwise pumping water or other fluid.

It is the object of the invention to provide a novel and improved mechanism for controlling and operating an electric switch which in turn controls the operation of an electric motor that drives the pump, the device being such that the switch is opened and closed with a quick movement by the rise and fall of the float or equivalent means.

A further object of the invention is the provision of a switch operating device of the nature indicated which is simple and inexpensive in construction, and thoroughly efficient, reliable and practical in use.

With the foregoing and other objects in view, which appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawings:—

Figure 1 is the diagrammatical view illustrating the pumping outfit and controlling and operating mechanism.

Fig. 2 is an elevation of the switch operating device with the parts in position to close the switch.

Fig. 3 is the longitudinal section of said device in position with the switch open.

Fig. 4 is the cross section on the line 4—4 of Fig. 3.

In carrying out the invention, there is provided a device 1 for opening and closing a switch 2 hinged to a switchboard or slab 3 and controlling the circuit 4 of an electric motor 5 which is connected by a belt 6 or otherwise with a pump 7. Connected to the inlet of the pump is a pipe 8 communicating with a waterbox or receptacle 9. If the apparatus is used for automatically pumping

the water out of a cellar, or the like, the receptacle or waterbox 9 is disposed at the lowest point of the cellar for the water to drain into the same, and from which the water is pumped. A pipe 10 connected to the pump 7 conducts the water to a suitable point of discharge, such as a drain, reservoir, or the like. A float 11 is movable within the receptacle 9 and connected thereto is a cord, cable or rope 12 passing over pulleys or guides 13 and having connected thereto a weight 14. The float 11 is heavier than the weight 14 thereby to pull the cable 12 with the float when the float is lowered, but when the float is buoyed up by the water in the receptacle 9 the weight 14 will pull the cable 12 in the opposite direction. Between the ends of cable 12 there is clamped thereon a pair of adjustable knobs 15 operating the device 1 to close the switch 2, when the weight 14 pulls the cable 12 due to the rise of the float 11, thereby starting the motor 5 which drives the pump 7 to pump the water out of the receptacle 9. As the water is pumped out the float 11 will lower pulling the cable 12 with it, and when the water level is lowered, the device 1 will be operated to open the switch 2 thereby stopping the motor and the pump until the receptacle 9 is again filled.

The device 1, which forms the gist of the invention, is of special construction whereby to open and close the switch by a sharp movement, which is desirable in an electric switch, for reasons well known. By opening and closing the switch by quick movement, the motor is stopped and started properly.

The device 1 embodies a rocking or oscillating ball runway 16 of elongated form, having attached to its intermediate portion an upwardly projecting arm or lever 17, and the runway 16 is pivoted intermediate its ends, as at 18, to a support of any suitable sort whereby the runway can swing about a horizontal axis past a horizontal intermediate position. The knobs 15 contact with the arm 17 when moved with the cable 12 and thereby tilt the runway 16 accordingly.

Plungers 19 and 20 are slidable within the ends of the runway 16 and are provided with flanges 21 at their outer ends. The two plungers are connected by longitudinal rods 22 at opposite sides of the runway 16, slidable in suitable guides 23 carried by the runway. The ends of the rods 22 extend through the flanges 21 and are secured adjustably.

thereto by means of nuts 24 threaded on the rods, thereby permitting the adjustment of the plungers 19 and 20 relatively. The rods 22 connect the plungers for simultaneous movement, whereby when one is forced outwardly the other will be slid inwardly. A leaf spring 25 is secured to each end of the runway 16 and provides a detent for the corresponding plunger, it being noted that when the plunger is moved inwardly the flange 21 thereof will move it into frictional engagement with the corresponding spring 25. This prevents the accidental movement of the plungers when in either position. A ball 26 rolls within the runway 16 for moving the plungers outwardly alternately, as the runway is tilted back and forth. The ball is held at either end of the runway until the same is tilted a certain amount, by the provision of leaf springs 27 secured upon the bottom of the runway and projecting toward the ends thereof, the free ends of the springs being raised by adjusting screws 28 threaded through the bottom of the runway and upon which the springs rest. The ball 26 can readily roll over the springs 27 toward the respective ends of the runway, but in rolling away from either end of the runway must pass over the stop formed by the free end of the spring 27. The springs 27 thus provide detents for holding the ball 26 at either end of the runway until the runway is inclined sufficiently to enable the ball to roll over the free end of the corresponding spring to the other end of the runway.

The operative connection between the device 1 and switch is accomplished by providing the free end of the switch with a slotted portion 29 engaging an outstanding stud 30 carried by rod 22 opposite the lever or arm 17.

The operation of the device is as follows: When the cable 12 is pulled by the lowering of the float 11, it will pull the arm 17 with the cable, and the runway 12 is therefore tilted to the position seen in Fig. 3, with the plunger 19 lowermost and the ball 26 bearing against said plunger. Now, as the receptacle 9 becomes filled with water, the float 11 will be raised up, thereby slackening the cable 12, which will be pulled by the weight 14, and said weight will carry the arm 17 with the cable. This will swing the runway 16 to and beyond its horizontal or intermediate position, and as the angle of inclination of the runway is changed, the ball 26 will tend to roll toward the left, but this is momentarily prevented by the right hand spring 27 until the runway 16 has reached such an inclination that the ball will roll downwardly with considerable gravity in the runway to strike the plunger 20 with such force as to disengage it from the respective spring 25 and move the plungers 19 and rods 22 toward the left. This will

swing the switch 2 with the rods 22 by a sharp movement to close the switch quickly and start the motor and pump. The device 1 will remain in this position until the water is pumped out of the receptacle 9, it being noted that as the water is pumped out, the float 11 will fall with the water level, thereby pulling the cable 12 and swinging the arm 17 toward the right. This will raise the plunger 20 with the runway 16, which plunger is, in the meantime, in its lowered position, as seen in Fig. 2. The ball 26 which bears against the plunger 20 will be held by respective spring or detent 27 until the runway 16 is inclined sufficiently to enable the ball to roll over this spring 27 and strike the plunger 19 with sufficient momentum to carry the plungers and rods 22 toward the right for quickly opening the switch 2, thus stopping the motor and pump.

The limited movement of the cable 12 will limit the movement of the device 1, although if necessary, the movement of the runway 16 can be limited by any suitable stops.

Having thus described the invention, what is claimed as new is:—

1. A switch operating device embodying a rocking runway, means for swinging it past a horizontal position, movable means carried by the runway for operating a switch, and a member movable within the runway for operating the last mentioned means.

2. A switch operating device embodying a rocking runway, means for moving it past horizontal position, reciprocatory means carried by the runway for operating a switch, and a member movable in the runway for moving the second mentioned means back and forth as the runway is tilted in opposite directions.

3. A switch operating device embodying a rocking runway, means for swinging same past horizontal position, plungers working within the ends of the runway, means connecting the plungers for operating a switch, and a member movable within the runway for moving the plungers outwardly.

4. A switch operating device embodying a rocking runway, means for swinging same past horizontal position, plungers working within the ends of the runway, means connecting the plungers for operating a switch, a member movable within the runway for moving said plungers outwardly, and detent means carried by the runway for holding said member at either end of the runway until it is inclined a certain amount.

5. A switch operating device embodying a rocking runway, means for swinging it past horizontal position, plungers for working in the ends of the runway, means connecting the plungers for connection with a switch to operate it, a member movable within the runway to strike the plungers and

move them outwardly, leaf spring detents carried by the runway and projecting toward the ends thereof for holding said member at either end of the runway until it is 5 inclined a certain amount, and adjustable means for raising and lowering the free ends of said detents.

6. A switch operating device embodying a rocking member, means for rocking said 10 member, switch operating means carried by

the member, and means movable on said member for operating the last mentioned means.

In testimony that I claim the foregoing as my own, I have hereto affixed my signature 15 in the presence of two witnesses.

JOHN BROWN.
